UNITED STATES PATENT OFFICE.

THOMAS WILLSON OBERT, OF EASTWOOD, NEW YORK, ASSIGNOR TO IROQUOIS CHINA COMPANY, OF SYRACUSE, NEW YORK, A CORPORATION OF NEW YORK.

DESIGN FOR A PLATE OR SIMILAR ARTICLE.

Application filed September 22, 1924. Serial No. 10,870. Term of patent 7 years.

To all whom it may concern:

Be it known that I, THOMAS WILLSON OBERT, a citizen of the United States, residing at Eastwood, in the county of Onondaga and State of New York, have invented a new, original, and ornamental Design for a Plate or Similar Article, of which the following is a specification, reference being had to the accompanying drawing, forming part thereof.

The figure is a plan view of a plate or similar article, showing my new design, the balance of the border being a repeat of the fragment of the design illustrated.

I claim:

The ornamental design for a plate or similar article, as shown.

THOMAS WILLSON OBERT.
